UNITED STATES PATENT OFFICE.

EDWARD J. MORIN, OF WYNOT, NEBRASKA.

POCKET PENCIL-HOLDER.

1,323,607.

Specification of Letters Patent.

Patented Dec. 2, 1919.

Application filed June 18, 1918. Serial No. 240,711.

To all whom it may concern:

Be it known that I, EDWARD J. MORIN, a citizen of the United States, residing at Wyo, in the county of Cedar and State of Nebraska, have invented certain new and useful Improvements in Pocket Pencil-Holders; and I do hereby declare the following to be a full, clear, and exact description of the invention, such as will enable others skilled in the art to which it appertains to make and use the same.

My invention relates to improvements in pencil holders especially adapted for carrying pencils on one's person.

An important object of this invention is to provide a device of the character described adapted for attachment to a coat pocket or other convenient place on one's garment.

A further object of the invention is to provide a pencil holder adapted for attachment to a garment, said pencil holder having means for carrying a number of pencils securely and permit of their ready removal.

A further object of the invention is to provide a device of the character described, which is of highly simplified construction, neat in appearance and cheap to manufacture.

A further object of the invention is to provide a device of the character described, which by virtue of its extreme simplicity and cheapness of manufacture, will meet with commercial favor in a highly crowded art.

Other objects and advantages of the invention will be apparent during the course of the following description.

In the accompanying drawings forming a part of this specification and in which like numerals are employed to designate like parts throughout the same,

Figure 1 is a front elevation of a garment pocket having my improved pencil holder applied thereto,

Fig. 2 is a front elevation of my improved pencil holder,

Fig. 3 is a horizontal section taken on line 3-3 of Fig. 2,

Fig. 4 is a central longitudinal vertical section through the same, and,

Fig. 5 is a side elevation of my improved pencil holder arranged in the pocket of a garment, the pocket being shown in section.

In the drawings wherein for the purpose

of illustration is shown the preferred embodiment of my invention, the numeral 10 generically designates the device, which in manufacture may be made of any suitable material, preferably metal.

The device comprises in part, a base 11 having secured thereto a coacting pencil retaining element 12. The member 12 is crimped to provide a plurality of longitudinally extending channels 13 adapted for the reception of pencils. The pencil retaining element 12 is provided at its four corners with retaining fingers 14 extending through apertures in the base 11 and bent thereupon. The base 11 is provided with a plurality of incisions thus forming partly severed portions 15. The partly severed portions 15 function as retaining elements or tongues for pencils and are disposed within and extend longitudinally of the channels 13 at points spaced from the ends of the same. As clearly shown in Fig. 4 a pencil may be inserted within any of the channels 13 and be engaged by the inwardly extending finger 15. In extending the tongues from the rear plate 11 and disposing them within the channels the same are prevented from catching the clothing, during the use of the device.

As clearly shown in Fig. 1, the device is adapted for attachment to the pocket 16 of a garment 17. A piece of spring wire bent for a greater portion of its length to form a substantially U-shaped member 18 is secured to the device and is adapted to extend over one side of the pocket as shown. The end portions 19 extend through apertures 20 in the base 11 of the device. As shown in Fig. 5 the end portions 19 contact with the rear of the base 11 only at their extreme ends and diverge outwardly therefrom. Disposed between the U-shaped portion 18 of the retaining element and the end portions 19 are crimped portions 21 coacting with the end portions 19 and functioning as springs to retain the U-shaped element 18 securely in engagement with the pocket.

In the use of my device, it will be apparent that the same is securely attached to a pocket by the U-shaped member secured thereto and is adapted for the reception of pencils.

While I have shown and described the preferred embodiment of my invention, it is understood that I may make such minor changes in arrangement and construction of

parts, as will remain within the spirit of the invention and the scope of the appended claims.

Having thus described my invention,
5 what I claim is:—

1. A pencil holder comprising, a body portion; a retaining element carried by the body portion; fingers carried by the coacting retaining element and extending through
10 the body portion and bent thereupon to secure the retaining element to the body portion, said retaining element being provided with a plurality of longitudinally extending parallel channels, said body portion being
15 provided with a plurality of incisions thus forming a plurality of partly severed portions disposed within said channels and spaced from the ends of the same; and means to attach the device to a garment.
- 20 2. A pencil holder comprising, a body

portion; a retaining element carried by the body portion and provided with a plurality of longitudinally extending parallel channels; fingers carried by the body portion and extending into said channels at points spaced 25 from the ends of the same and means to attach the device to a garment, said means comprising a piece of spring wire bent between its ends to form a U-shaped member adapted to be arranged on one side of a 30 pocket and having its end portions extending through the body portion and bent to form spring devices.

In testimony whereof I affix my signature in presence of two witnesses.

EDWARD J. MORIN.
